[57] CLAIM

The ornamental design for an walk-in automatic teller building, substantially as shown and described.

DESCRIPTION

FIG. 1 is a perspective view of the walk-in automatic teller building;

FIG. 2 is a front view of the design;

FIG. 3 is a rear view of the design;

FIG. 4 is a side view of the design;

FIG. 5 is an opposite side view of the design; and

FIG. 6 is a top view of the design of the present invention.
